CLAIM

The ornamental design for an evaporation panel, as shown and described herein.

DESCRIPTION

FIG. 1 is an upper left perspective view of an evaporation panel;

FIG. 2 is a lower left perspective view of the evaporation panel;

FIG. 3 is a front plan view of the evaporation panel;

FIG. 4 is a back plan view of the evaporation panel;

FIG. 5 is a left side plan view of the evaporation panel;

FIG. 6 is a right side plan view of the evaporation panel;

FIG. 7 is a top plan view of the evaporation panel; and,

FIG. 8 is a bottom plan view of evaporation panel.

1 Claim, 5 Drawing Sheets
